PUMP

James E. Bevins, Ramsey Estates, N. J., assignor
to Bendix Aviation Corporation, Teterboro,
N. J., a corporation of Delaware

Application June 21, 1946, Serial No. 678,481

11 Claims. (Cl. 103—174)

1

This invention relates to pumps and the like, particularly of the cylinder and piston type, and to novel means for sealing the pistons relative to the cylinders.

A pump piston of standard type, operating in a cylinder of uniform bore, has heretofore been sealed against leakage through the clearance between the piston and the cylinder wall, as by a ring or rings of metal, fiber, composition or the like.

Such structure is effective at certain pressures for pumping certain fluids, but not adapted for other service, where the highest mechanical efficiency, high speed operation and low wear are of great importance. The latter conditions are present in pumping fuel for jet propelled aircraft where the fluid is of low viscosity and lubricity.

Structures have also been suggested to seal pump pistons against such leakage by the counterpressure of a sealing fluid, but such pressure has been controlled separately from, and independently of, the pressure of the fluid being pumped, with the result that the structures are complicated, cylinders of different bores are required, and the pressure regulating means, when set for a certain pressure, is not effective at other pressures unless reset by hand, which is not feasible in a pump called upon to operate at different pressures.

Devices for pumping fluid of low viscosity, such as gasoline, have required extremely close fitting parts to create high pressures, such fit being difficult and expensive to produce, and subject to early ineffectiveness from wear whereby the fluid leaks past the piston to lower the quantity and pressure of the fluid being delivered.

An object of the invention is to provide a pump of the aforementioned character which remedies the faults stated, and does so by novel improved means.

Another object is to provide means including a piston unit or the like in which the unit comprises a plurality of piston elements movable together to effect the unit pumping action, and which elements have pumping action relative to each other dependent upon the pressure of the fluid being pumped to force a sealing fluid into position sealing the unit at a pressure preventing the passage of any substantial amount of either fluid past the piston.

Another object is to provide a unit, as aforesaid, which is adapted to operate in a cylinder portion of one uniform bore.

Another object is to provide novel means adapted to pump fluid and to seal a movable pumping element or piston therefor against leakage of

2

such fluid past such element from its pumping side to its opposite side, and providing such element with greater clearance relative to a cylinder or chamber wall than such fluid would normally require for such sealing.

Another object is to provide a novel movable pump unit or piston, in which the unit is provided with means forming a fluid piston ring or the like instead of the usual ring of metal.

10 Another object is to provide novel operating means for the piston unit, such as an eccentric cam having passageway means through which the passage of sealing fluid is controlled in predetermined relation to a position of the piston

15 during its stroke.

A further object is to provide a pump of the above-indicated character that is simple and durable in construction, economical to manufacture, and effective in its operation.

20 These and other objects and features of the invention are pointed out in the following description in terms of the embodiment thereof which is shown in the accompanying drawings. It is to be understood, however, that the drawings

25 are for the purpose of illustration only, and are not designed as a definition of the limits of the invention, reference being had to the appended claims for this purpose.

In the drawings, wherein like reference characters refer to like parts in the several views:

Figure 1 is a view, partially in end elevation and partially in section, along a line 1—1 of Figure 3, of a pump constructed in accordance with one form of the invention;

30 Figure 2 is a detail of certain parts, as seen in Figure 3;

Figure 3 is a view partially in end elevation and partially in section substantially along the line 3—3 of Figure 1; and

35 Figure 4 is a view similar to Figure 2 of a modified form of the structure thereof.

Referring to Figures 1 and 3, one form of pump embodying the invention comprises, in general, a casing 10, including a main or central body 12, an end member 14 and an end element 16, a rotor 17 and piston units 19.

The body 12 forms an inner chamber 18 for the rotor 17 and for a lubricating fluid, such as oil, and open at one side 20, at the left as viewed in

50 Figure 3, and is provided with a plurality of radial cylinders 22 disposed about and open to the chamber 18. A wall 24, closing the opposite side of the chamber 18, provides an inner bearing pocket or receiving means for an anti-friction bearing 23. The body also comprises inlet valve chambers 28, in this instance for a fluid of low

lubricative character, such as gasoline, to be pumped, each of the chambers 28 being disposed between two of the cylinders 22, and having a local inlet 30 from the closed side of the body 12, and a local duct 32 to a next adjacent cylinder, to the right or clockwise thereof, as viewed in Figure 1. The body 12 further comprises a local outlet 34 from each of the cylinders 22 for the gasoline to the closed side of the body. Plugs 36 and 38 close the outer ends of the cylinders 22 and the valve chambers 28, respectively.

The end member 14, see Figure 3, secured to the closed side of the body 12, as by bolts 40, is provided with a main inlet 42 and a main outlet 44 for the gasoline, a portion 46 of the member 14 cooperating with the wall 24 to provide a manifold 47 between the main inlet 42 and the local inlets 30. The member 14 has an outlet valve chamber 48 for each of the local outlets 34, and a manifold 50 between the main outlet 44 and each of the outlet valve chambers 48.

Poppet valve members 52 and 53, normally biased closed by springs 54 and 55, respectively, are disposed in the valve chambers 28 and 48, respectively.

The end element 16, secured to the open side 20 of the body 12, as by bolts 56, is provided with a counter-balance element receiving space 57, bearing means or a portion 58 for receiving a bearing, and oil inlet and outlet ports 60 and 62, respectively, communicating with the chamber 18 of the body 12.

The rotor 17, as better shown in Figure 3, comprises a shaft 64 having one splined end 66, for attachment to a motor, and its opposite end splined into a portion 68 of the rotor. A portion 70 of the rotor supports the inner race of an anti-friction bearing 72, the outer race of which is disposed in a ring 74 press fitted in a recess in the end element 16 and having a flange 76.

Another ring 78 closely fits within the flange 76 and is connected to an annular end plate 80 by a bellows 82 fixed and sealed relative to both the ring 78 and the plate 80, the latter of which is secured to the end element 16, as by screws 84.

To the right of the portion 68, as shown in Figure 3, the rotor 17 further comprises a counterbalance weight sector 86 in the space 57, an eccentric cam portion 88 in the chamber 18, and a portion 90 supporting the inner race of the anti-friction bearing 23 in the pocket formed by the wall 24.

The rotor 17 is provided with a bore 94 closed at one end 96 and open at its opposite end 98 to the oil in the inner chamber 18 of the body 12. The cam sector 88 has a peripheral slot 100 intersecting the bore 94 in communication therewith and with the oil in the chamber 18.

Each piston unit 19, as better seen in Figure 2, comprises, in this instance, a piston or sleeve 102, in one of the cylinders 22, having an open spherically curved inner end 104, and an annular outer groove 106 communicating with the interior of the sleeve by a plurality of small radial holes 108. An auxiliary piston 110, of substantially cupshape, has an annular exterior groove 112, and port 112' placing the interior of the auxiliary piston 110 in communication with the groove 112. The auxiliary piston 110 has its closed end 114 biased by a spring 116 toward a lock ring 118, which is disposed in an inner groove of the sleeve 102. The spring 116 extends between the piston 110 and an auxiliary sleeve 120 in the piston sleeve 102.

A link 122 is pivotally connected, at one end,

as by a pin 123, to the auxiliary sleeve 120 and to the piston sleeve 102, and has a cross portion 123', at the other end, linked to the shoe 124. The shoe has a recess conforming to, and slidably or pivotally receiving, the spherically curved end 104 of the sleeve 102, and a surface 126 conforming to the curvature of the cam 88. A recess 128, at the cam engaging side of the shoe 124, communicates, through an aperture 130 in the shoe, with the interior of the sleeve 102 and forms, in this instance, a substantially rectangular frame or flange 132 entirely around the recess 128 on the cam 88. The shoe 124 is further provided, in this instance, with arcuate opposite side grooves 134, Figures 1 and 3, in which are disposed rings 136. The latter are joined, axially of the cam, by clips 138, Figures 1 and 3, disposed between certain of the sleeves, to maintain the shoes in the various positions thereof determined by the cam 88.

In operation, when the rotor 17 rotates, each unit 19 reciprocates, with the pistons 102 and 110 operating together, or in concert, to create a pumping action between the gasoline inlet and outlet ports 42 and 44, respectively.

Referring to Figure 2, and assuming that there is resistance to the flow in the outlet line, as by the injection nozzles of a jet engine, with the unit 19 at the end of its gasoline discharge compression stroke, at the top of the unit, in Figure 2, at a position indicated by a broken line 140, the unit is full of oil and closed by the cam 88, since the slot 100 at this time has not reached the shoe 124. Also, the top of the auxiliary piston 110 is in initial position spaced from the lock ring 118 therebelow, as will further appear.

When the unit descends from this position, gasoline is drawn from the main inlet 42 into the manifold 47, and through the local inlet 30 to lift the valve member 52, and pass the liquid through the duct 32 into the cylinder 22. At this time, the outlet valve member 53 is maintained closed by the spring 55 and by the suction of the unit 19.

Upon continued descent of the unit 19, toward the end of its suction stroke shown in Figure 2, near this end or fastest part of its gasoline suction stroke, the slot 100 has arrived opposite the shoe 124, whereupon the auxiliary piston 110 rises against the lock ring 118 to create suction on the oil in the chamber 18 to draw into the unit 19 an amount of the oil equal to any which may have escaped along the cylinder walls between the latter and the unit 19.

When the unit is subsequently raised, from its position of Figure 2, the cam slot 100 passes the shoe 124 to close off the oil communication with the chamber 18, whereupon the auxiliary piston 110 pressing against the gasoline is returned to its initial position spaced from the lock ring 118, during which it exerts pressure on the oil to force it through the ducts 108 into the groove 106 wherein it forms, in effect, a piston ring of oil at a pressure dependent upon and relative to the pumping pressure of the gasoline preventing the passage of any substantial amount of either the gasoline or the oil through the clearance between the unit 19 and the walls of its cylinder 22.

The oil pressure, referred to above, may be rendered substantially equal to the gasoline pumping pressure because the effective area of piston 110 subjected to gasoline pressure is equal to that subjected to oil pressure created by the

pumping action between the piston 102 and the piston 110.

By the structure described, the clearance between the unit 19 and the walls of its cylinder 22, may therefore be only such as to seal the unit by the oil, which clearance is considerably more readily provided than the very close tolerance which would be necessary to seal the unit by the gasoline. A tolerance for effective sealing by gasoline, especially in view of the low lubricative property of gasoline, would also cause undue wear of the piston unit and the cylinder, whereby the pump would soon become reduced in its effectiveness and be required to be rebuilt or abandoned long before attaining any period of usefulness comparable to that of the pump of the present invention.

The invention, therefore, provides a pump which is easier and more economical to manufacture, more rugged and durable, and of longer life, and which has other advantages over former pumps for comparable service.

In Figure 4, showing a modification of a portion of the invention, corresponding parts are designated by corresponding reference numerals, and modified parts by corresponding reference numerals having the suffix (a). In this form, there are differences of structure from that above described, wherein a unit 109a has a main gasoline piston 102a in the form of a closed end thimble having a groove 106a and holes 108a leading from the interior of the thimble to the groove 106a.

An auxiliary piston 110a is slidably fitted in the piston 102a, and has an apertured rounded end 104a fitting the shoe 124. A spring 116a extends between the piston 110a and the closed end wall of the piston thimble 102a.

In this form also, although the results are substantially the same, there is the difference in operation wherein, when the unit descends from its initial position at the end of its gasoline discharge stroke at the start of its suction stroke, the piston 102a is retarded by the suction relative to the piston 110a whereby the latter is moved, by the spring 116a in following the shoe 124 on the cam 88, in advance of the piston 102a to position wherein, near the end or fastest part of the suction stroke, the piston 102a moves reversely relative to the piston 110a to force oil, as above described, through the rotor 17, and the shoe 124 into the unit 19a, and through the ducts 108a into the groove 106a.

The oil pressure created by the pumping action between the pistons 102a and 110a will be higher than the gasoline pumping pressure due to the difference in area between the pistons 102a and 110a. This higher pressure however may be desirable under some conditions where more oil sealing pressure is necessary. To employ this higher pressure to accomplish the desired results, the location of the oil groove 106a may be varied along the piston 102a.

Although only two embodiments of the invention have been illustrated and described, various changes in the form and relative arrangements of the parts, which will now appear to those skilled in the art, may be made without departing from the scope of the invention. Reference is, therefore, to be had to the appended claims for a definition of the limits of the invention.

What is claimed is:

1. A pump comprising a pump casing including a body having an inner chamber open at one end, a plurality of radial cylinder disposed about

and open to the chamber, a wall closing the opposite end of the chamber, valve chambers for a fluid to be pumped, each of said valve chambers being disposed between two of the cylinders and having a local inlet from the other side of said closed end and a local duct to a next adjacent corresponding one of the two cylinders, and a local outlet from each of the cylinders for the fluid to said outer side, means closing the outer ends of the cylinders and valve chambers, an end member secured to said body over said closed end having a main inlet and a main outlet for the fluid, a portion cooperating with said wall to provide a manifold between said main inlet and said local inlets, an outlet valve chamber for each of said local outlets, and a manifold between the main outlet and each of the outlet valve chambers, a valve in each of the local inlet and outlet valve chambers, an end element secured to said open end, a rotor in the casing journaled in said wall and in said element and adapted to be driven from outside the casing and including an eccentric cam in said inner chamber having an opening for passing another fluid from the latter chamber, and a piston unit in each of the cylinders having an apertured shoe on the cam and adapted to pump said first fluid and to seal the unit against leakage thereof past the unit from its pumping side to its opposite side through clearance between the unit and its cylinder wall, the unit including a plurality of piston elements movable together to pump said first fluid and having relative pumping action dependent upon the pressure of said first fluid to force said second fluid from said inner chamber through the cam opening and the shoe to position between the piston elements sealing said clearance at a pressure relative to the pumping pressure of said first fluid preventing the passage of any substantial amount of either fluid through said clearance.

2. A pump comprising means forming a chamber, a plurality of radial cylinders closed at the outer ends and disposed about and open to the chamber, local inlet valves for a fluid to be pumped, each of said valves communicating with one of the cylinders, a local outlet valve from each of the cylinders for the fluid, a main outlet and a main inlet for the fluid, a manifold between the main inlet and the local inlet valves, a manifold between the main outlet and the local outlet valves, a rotor including an eccentric cam having an opening for passing another fluid from said chamber, and a piston unit in each of the cylinders riding on the cam open thereto and adapted to pump said first fluid and to seal the unit against leakage thereof past the unit from its pumping side to its opposite side through clearance between the unit and its cylinder wall, the unit including a plurality of piston elements movable together to pump said first fluid and having pumping action relative to each other dependent upon the pressure of said first fluid to force said second fluid from said chamber through said cam opening to position between the piston elements sealing said clearance at a pressure relative to the pumping pressure of said first fluid preventing the passage of any substantial amount of either fluid through said clearance, said cam alternately closing and opening each of said units to said chamber.

3. A pump comprising means forming a chamber, a cylinder closed at one end and open at the other end to the chamber, an inlet valve for

a fluid to be pumped communicating with the cylinder, an outlet valve from the cylinder for the fluid, a rotor including an eccentric cam having an opening for passing another fluid from said chamber, and a piston unit in the cylinder riding on the cam and open thereto and adapted to pump said first fluid and to seal the unit against leakage thereof past the unit from its pumping side to its opposite side through clearance between the unit and the cylinder, the unit including a plurality of piston elements movable together in pumping said first fluid and adapted, and having movement relative to each other dependent upon the pressure of said first fluid, to pump force said second fluid from said chamber through the cam opening to position between said piston elements sealing said clearance at a pressure relative to the pumping pressure of said first fluid preventing the passage of any substantial amount of either fluid through said clearance, the cam being adapted to open and close said unit to said chamber.

4. In a pump including a cylinder, the combination of a piston unit adapted for operation in the cylinder to pump a fluid and to seal the unit against leakage of the fluid past the unit from its pumping side to its opposite side through clearance between the unit and the wall of the cylinder, said unit comprising a plurality of pumping piston elements movable together in the aforesaid pumping action and adapted, and having relative movement, to effect another pumping action dependent upon the pressure of said fluid, operating means for the unit including means supplying another fluid to the opposite side of said unit from a source separate from said piston unit, said other pumping action forcing said other fluid into position sealing said clearance at a pressure proportional to but greater than the pumping pressure of said first fluid preventing the passage of any substantial amount of either fluid through said clearance.

5. In a pump including a chamber, the combination of a unit adapted for operation in the chamber to pump a fluid and to seal the unit against leakage of the fluid past the unit from its pumping side to its opposite side through clearance between the unit and the wall of said chamber, said unit comprising a plurality of pumping elements movable together in the aforesaid pumping action and adapted, and having relative movement, to effect pumping action dependent upon the pressure of said fluid to force another fluid into position sealing said clearance at a pressure relative to the pumping pressure of said first fluid preventing the passage of any substantial amount of either fluid through said clearance, and an apertured shoe through which said second fluid passes to said position, and operating means for the unit including a cam on which the shoe rides and which controls the passage of said second fluid through the shoe.

6. In a pump including a chamber, the combination of a piston unit adapted for operation in the chamber to pump a fluid and to seal the unit against leakage of the fluid past the unit from its pumping side to its opposite side through clearance between the unit and the wall of said chamber in which the unit operates, said unit comprising a plurality of pumping piston elements movable together in the aforesaid pumping action and adapted for relative movement to each other dependent upon the pressure of said fluid, operating means for the unit including means supplying another fluid to the opposite

side of said unit from a source separate from said piston unit, said relative movement of said piston elements under the pressure of said first fluid forcing said other fluid into position sealing said clearance at a pressure relative to the pumping pressure of said first fluid preventing the passage of any substantial amount of either fluid through said clearance, one of said piston elements being of substantially sleeve formation open at said pumping side, and another thereof closing the sleeve opening adjacent to said pumping side.

7. In a pump including a chamber, the combination of a unit adapted for operation in the chamber to pump a first fluid and to seal the unit against leakage of the first fluid past the unit from its pumping side to its opposite side through clearance between the unit and the wall of said chamber, said unit comprising a plurality of pumping elements movable together in the aforesaid pumping action and adapted for relative movement to effect a relative pumping action dependent upon the pressure of said fluid, spring means biasing one of said pumping elements in a direction opposing the pressure of said first fluid and assisting said pumping elements in said relative pumping movement, a source of a second fluid, and operating means for the unit including means for supplying said second fluid to the opposite side of said unit, said relative pumping action forcing said second fluid into position sealing said clearance at a pressure dependent upon and relative to the pumping pressure of said first fluid thereby preventing the passage of any substantial amount of either fluid through said clearance.

8. In a pump including a chamber, the combination of a unit adapted for operation in the chamber to pump a first fluid and to seal the unit against leakage of the first fluid past the unit from its pumping side to its opposite side through clearance between the unit and the wall of said chamber, said unit comprising, a source of a second fluid, a plurality of pumping elements movable together in the aforesaid pumping action and adapted for relative movement to effect a relative pumping action dependent upon the pressure of said first fluid to force said second fluid into position sealing said clearance at a pressure dependent upon and relative to the pumping pressure of said first fluid preventing the passage of any substantial amount of either fluid through said clearance, and means for operating said unit including means for controlling and causing said second fluid to flow from said source of the opposite side of said unit at a predetermined position of the stroke of the unit.

9. In a pump including a chamber, the combination of a unit adapted for operation in the chamber to pump a first fluid and to seal the unit against leakage of the first fluid past the unit from its pumping side to its opposite side through clearance between the unit and the wall of said chamber, said unit comprising a source of a second fluid, a plurality of pumping elements movable together in the aforesaid pumping action and adapted for relative movement to effect a relative pumping action dependent upon the pressure of said first fluid to force said second fluid from its source into position sealing said clearance at a pressure dependent upon and relative to the pumping pressure of said first fluid preventing the passage of a substantial amount of either fluid through said clearance, and operating means for said unit having passageway

means from said source of the second fluid to said clearance sealing position for said second fluid.

10. In a pump including a chamber, the combination of a unit adapted for operation in the chamber to pump a first fluid and having in effect a piston ring groove to seal the unit against leakage of the first fluid past the groove from the pumping side of the unit to its opposite side through clearance between the unit and the wall of said chamber, said unit comprising a source of a second fluid, means for supplying said groove with said second fluid, and a plurality of pumping elements movable together in the aforesaid pumping action and adapted to have a relative movement to effect a relative pumping action dependent upon the pressure of said first fluid to force said second fluid into said groove sealing said clearance at a pressure dependent upon and relative to the pumping pressure of said first fluid preventing the passage of any substantial amount of either fluid through said clearance.

11. In a pump including a chamber, the combination of a unit adapted for operation in the chamber to pump a first fluid and to seal the unit against leakage of the first fluid past the unit from its pumping side to its opposite side through clearance between the unit and the wall

of said chamber, said unit comprising a source of a second fluid, a plurality of pumping elements movable together in the aforesaid pumping action and adapted to have a relative movement to effect a relative pumping action dependent upon the pressure of said first fluid to force said second fluid into position sealing said clearance at a pressure dependent upon and relative to the pumping pressure of said first fluid preventing the passage of any substantial amount of either fluid through said clearance, and means for supplying said second fluid to the opposite side of said unit from said source aforesaid.
